RADIO PROTECTIVE DEVICE

Lowell M. Hollingsworth, Cambridge, and Louis D. Smullin, Arlington, Mass., assignors, by mesne assignments, to the United States of America as represented by the Secretary of War

Application February 8, 1945, Serial No. 576,843

5 Claims. (Cl. 343—5)

1

The present invention relates to radio object-locating systems, adapted to transmit and receive pulses of high frequency energy, and it is particularly directed to a device for protecting the receiver component of such a system from high intensity pulses.

In a system of the above type, whenever a single antenna is used for both transmitting and receiving, the problem arises of insuring that maximum use is made of the available energy. One solution is to provide a transmit-receive or "TR" switch to transfer the antenna connection from the receiver to the transmitter for the duration of the transmitted signal pulses. An important function of the switch is the protection of the receiver input circuit. At frequencies where RF amplifiers may be used, the amplifier tube in the input stage can be chosen to withstand large input powers without damage. However, at microwave frequencies, the input stage includes a mixer which may be easily damaged by large applied signals and so must be more carefully protected. This is particularly true of crystal mixers which are extremely delicate.

When the power of a radio object-locating set is on, the delicate crystal in the receiver circuit is usually protected from large doses of RF energy, for example, by the spark-gap of a cavity type TR switch which breaks down when it is overloaded, thus shorting out the receiver. As is well-known, a "keep-alive" voltage is applied across the gap to maintain a glow discharge to provide ions for quickly forming an arc across the spark-gap when the transmitted pulse is applied. When the power is off, however, the "keep-alive" voltage across the gap is off, the gas in the TR cavity is not ionized, and breakdown of the gap cannot occur rapidly enough to protect the crystal. Therefore, when the "keep-alive" of the set is not on, the receiver crystal is susceptible to damage, particularly from large output signals of nearby radio object-locating sets. There is also danger that the crystal may be damaged as a result of misfiring of the magnetron of the transmitting apparatus on starting.

It is one of the objects of the present invention to provide means for protecting the receiver circuit of a radio object-locating apparatus from overload when the "keep-alive" of a TR switch is not in operation.

It is another object of the invention to provide a mechanical device which is adapted to prevent large RF transmitted pulses from entering the receiver circuit.

2

It is still another object of this invention to provide, in association with a TR cavity coupled by means of an iris to a receiver transmission line, a movable mechanical shutter or shield for protecting the receiver crystal by shielding the iris from the cavity field and by shorting-out coupling currents.

Other objects and advantages of the invention will become apparent as the description 10 proceeds, reference being made to the drawings in which:

Fig. 1 is a top plan view of a TR cavity coupled to a wave guide and to a receiver transmission line and embodying the device according to the 15 present invention;

Fig. 2 is a sectional view along the line 2—2 of Fig. 1, and

Fig. 3 is a sectional view, partly broken away, along the line 3—3 of Fig. 2.

20 A preferred embodiment of the invention is illustrated in the drawings in which 10 indicates a cavity type TR box or switch of conventional design, having a spark-gap formed by two opposing electrodes generally indicated at 11 mounted on the end walls 12 and 13 of box 10. Box 10 is coupled in any suitable manner to a transmission line 14 connecting a transmitter apparatus 40 to an antenna 42 and to a transmission line 15 connecting to a receiver 44. Lines 14 and 15 are shown preferably as a wave guide and a coaxial line respectively, suitably coupled to box 10, for example, as shown, by means of irises or apertures 16 and 17.

Disposed in side wall 18 of box 10 and near 35 the coupling to line 15 is a longitudinal slot 19 having its longitudinal axis substantially perpendicular to end walls 12 and 13. Slot 19 is relatively narrow in width and has a length substantially equal to the width of side wall 18 for 40 permitting entry of a shutter member 20 into the cavity defined by box 10. Shutter member 20 may be a flat rectangularly shaped strip but as shown is preferably a curved or arcuate strip or sheet of metal or other suitable electrical conducting material preferably shaped as a portion of a cylindrical surface. Member 20 is mounted in any suitable manner so that it may be moved into and out of the cavity of box 10 through slot 19. For example, member 20 may be rigidly 45 mounted on an arm 21 to rotate therewith about a pivot 22. Member 20 may be actuated in any desired manner, such as by a solenoid 23 through lever mechanism generally indicated at 24. The solenoid and lever mechanism are so arranged 50 that when power source 46 is turned off, the

shutter member 20, which is normally in the position indicated by dotted lines in Fig. 3 when the system is in operation, is adapted to be automatically swung into box 10 through slot 19 and into position in front of the iris 17. Also the shutter member 20 may be adapted to be automatically withdrawn from the cavity when the power is turned on. However it has been found desirable to provide a separate control for selectively operating the solenoid or other actuating means when the power of the set is turned on whereby the shutter 20 may be moved out of box 10 or maintained in position to shield the receiver apparatus against damage such as may be caused by misfiring of the magnetron of the transmitting apparatus on starting.

It should be noted that in addition to shielding the coupling aperture 17 from the fields in the cavity of box 10, shutter member 20 should be brought into good electrical contact with the transmission line 15, or as shown the outer conductor of the coaxial line 15, so that currents that would ordinarily induce voltages in the iris coupling 17 are adapted to be shorted-out through shutter member 20. To accomplish this shutter member 20 is preferably moved a sufficient distance into box 10 to be in front of iris 17 and in slidably but firm contact with the wall portions of transmission line 15 adjacent to iris 17. Similarly, the short-circuiting action may be achieved by shutter member 20 making good contact with end walls 12 and 13 of box 10. Also shutter member 20 may make contact with the side wall 18 at slot 19 and by engagement or abutment of the free end of shutter 20 with the inside surface of side wall 18 or the far side of coupling 17 as at 25, to further insure good shielding action.

It will be understood that not only is shutter 20 adapted to protect the receiver by shielding the iris 17 from electromagnetic fields in the cavity and by shorting-out coupling currents, but the insertion of shutter member 20 also serves to detune the TR cavity.

While a preferred embodiment of the invention has been described above and illustrated in the drawings, it will be understood that the invention is capable of modification and improvement. For example, the shutter member 20 may be a flat plane member. Also, instead of being insertable through a slot in the side wall of the TR cavity, member 20 may be inserted through a straight or arcuate slot in one of the end walls 12 or 13, and if desired, slidably guided into place by means of grooves provided in the side wall 18 at points 19 and 25. Movement of this member 20 may be actuated by mechanical or electrical means; for example, by a relay or other tripping mechanism. Therefore, it is not desired that the present invention be limited to the precise details set forth.

What is claimed is:

1. A radio object-locating system operable from a source of electric power and comprising, in combination, an antenna for transmitting and receiving pulsed electromagnetic energy, transmitting apparatus electrically connected to said antenna thru a pair of transmission lines and receiving apparatus, wave transmission means including a walled cavity type transmit-receive switch electrically coupled to said transmission lines, the said switch being adapted to afford operative connections from said antenna alternatively to said transmitting apparatus and to said receiving apparatus, said switch enabling

said wave transmission means to pass electromagnetic energy from said transmitting apparatus to said antenna and having a portion thereof in which a coupling is normally effected between said antenna and said receiving apparatus except for the duration of energy pulse transmissions by said system, a sheet-like electrically conductive member arranged to be pivotally inserted through a suitable slot in the wall of said switch, means under control of said power source for moving said member and operative when said system is cut off from said power source to move said member into electrical contact with portions of said transmission means affording connection to said receiver apparatus adjacent said coupling portion for effecting cavity detuning and short-circuiting action thereby to protect said receiving apparatus from energy fields within said switch.

2. The combination, as claimed in claim 1, wherein the transmit-receive switch comprises a cavity defined by opposing parallel plane end walls and a circular side wall perpendicular to said end walls, wherein the coupling portion comprises an iris coupling providing communication between said cavity and said transmission means connecting to said receiver apparatus, the slot being disposed in said side wall with its longitudinal axis perpendicular to said end walls, the length of said slot being substantially equal to the width of said side wall, and wherein the sheet-like member is shaped as a portion of a cylindrical surface having a width substantially equal to the length of said slot and sufficient to make contact with said end walls and a length sufficient to make good contact with said side wall at said slot and at the opposite side of said iris coupling.

3. The combination as claimed in claim 1 wherein the transmission means connecting the switch to the receiver apparatus is a co-axial transmission line, said coupling portion comprising an iris in the outer wall of said line providing communication between said line and the cavity of said switch and wherein the sheet-like member is adapted to be moved into electrical contact with wall portions of said line adjacent said iris.

4. A switch of the transmit-receive walled cavity type for use in a radio object-locating system operable from a source of electric power having an antenna for transmitting and receiving pulsed electromagnetic energy, transmitting apparatus and receiving apparatus, comprising, in combination, means for coupling said cavity to said transmitting and receiving apparatus, a wall portion of said switch having a slot, a member shaped as a portion of a cylindrical surface being insertable into said cavity through said slot into a position in front of said means coupling said cavity to said receiving apparatus, the curved edge portions of said member making good electrical contact with the adjacent wall portions of said switch, and means for moving said member into said position whereby said member is adapted to shield said coupling for protecting said receiving apparatus from damage by large signal pulses.

5. A switch of the transmit-receive walled cavity type for use in radio object-locating system operable from a source of electric power and having an antenna for transmitting and receiving pulsed electromagnetic energy connected to a transmitting apparatus and a receiving apparatus through transmission means, said switch including means for coupling said switch to said transmission means, a wall portion of said switch

having a slot, a sheet-like member insertable into the cavity of said switch through said slot into position to shield said last mentioned coupling means and into good electrical contact with portions of said transmission means connecting said switch to said receiving apparatus adjacent said last mentioned coupling means, and control means for moving said member into said position thereby protecting said receiving apparatus from damage by unwanted signal pulses, said control means being normally automatically operable when said apparatus is cut-off from said

power source and selectively operable when said apparatus is connected to said power source.
